UNITED STATES PATENT OFFICE.

JOHN W. KIRKUS, OF SHAWMUT, ALABAMA.

LOOM.

1,006,228.

Specification of Letters Patent. Patented Oct. 17, 1911.

Application filed June 7, 1910. Serial No. 565,457

To all whom it may concern:

Be it known that I, JOHN W. KIRKUS, a citizen of the United States of America, residing at Shawmut, in the county of Chambers and State of Alabama, have invented 5 new and useful Improvements in Looms, of which the following is a specification.

This invention relates to looms, and it has for its object to provide a simple and improved means for actuating the picker sticks by means of compressed air, whereby said picker sticks shall be actuated positively, efficiently and in such a manner that the return movement to each picker stick will be 15 cushioned by the air that is being exhausted.

A further object of the invention is to simplify and improve the general construction and operation of a device of the character outlined above.

With these and other ends in view which will readily appear as the nature of the invention is better understood, the same consists in the improved construction and novel arrangement and combination of parts 25 which will be hereinafter fully described and particularly pointed out in the claim.

In the accompanying drawing has been illustrated a simple and preferred form of the invention, it being, however, understood 30 that no limitation is necessarily made to the precise structural details therein exhibited, but that changes, alterations and modifications within the scope of the invention may be resorted to when desired.

In the drawing,—Figure 1 is a sectional front elevation, showing a portion of the frame of a loom together with such parts as are necessary to an understanding of the invention. Fig. 2 is a sectional detail view 40 taken on the line 2—2 in Fig. 1. Fig. 3 is a detail elevation illustrating a modification. Fig. 4 is a sectional detail on the line 4—4 in Fig. 3.

Corresponding parts in the several figures 45 are denoted by like characters of reference.

The frame A of the improved loom is provided with uprights 2, 2 supporting cylinders 3 wherein pistons 4 are arranged for reciprocation, said pistons being each provided 50 with a stem 5 extending through the head 6 at the outer end of the cylinder. The frame is provided with brackets 7 upon which the levers 8 constituting the picker sticks are pivoted, the lower ends of said 55 picker sticks being movably connected with the piston stems 5 by means of pins 9 en-

gaging slots 10 adjacent to the lower ends of the picker sticks. Said picker sticks are designed in the usual manner to operate the shuttle 11.

12 is the lay of the loom.

A feed pipe 13 is connected at one end with a source of supply of compressed air, the other end of said pipe being extended, if desired, to supply the picker-actuating mechanism of a series of looms. The inner ends or heads of the cylinders 3 are provided with air inlets 14 communicating through a branch pipe 15 with the supply pipe 13, said inlets 14 being intersected by valve casings 16 wherein valves 17 are arranged for reciprocation. Each of the valves 17 is provided with an inlet port 18 for the passage of air to the cylinder from the source of supply and with an exhaust port or passage 19 through which the interior of the cylinder 75 may communicate with the atmosphere. It is obvious that when the device is in operation, the valve appended to each cylinder alternately places such cylinder in communication with the supply and with the exhaust ports, the two positions being clearly indicated in Fig. 1 of the drawings.

A driven shaft 20 supported in suitable bearings is provided with suitable means, 85 such as a sprocket wheel 21, whereby it may be driven from a suitable source of power. In Fig. 1 the shaft 20 is shown equipped with pinions 22, meshing with suitably supported spur-wheels 23, the faces of which are 90 provided with cam grooves, as shown at 24 in Fig. 2. Each of the valves 17 has a stem 25 provided with an anti-friction element, such as a roller 26 engaging the cam groove 24 of one of the spur wheels. It is obvious 95 that when the spur wheels are rotated the valves will be actuated to reciprocate in their respective casings, and it is further obvious that the arrangement is such that when the cylinder at one side of the frame 100 communicates with the air supply, the cylinder at the opposite end of the frame is in communication with the atmosphere through the exhaust. A pressure gage 27 may be provided if desired.

Under the construction illustrated in Figs. 3 and 4 the driven shaft 20 is provided at either end with an eccentric disk 28 having a strap 29 provided with a stem 30 which is pivotally connected with one of the valve 110 stems 25 to which reciprocatory motion will thus be imparted. It is obvious that within

the scope of the invention other well known mechanical means may be provided for actuating the valves.

In the operation of this device, when the shaft 20 is rotated, the valves will be actuated, and air will be alternately admitted to and exhausted from the cylinders at the two sides of the loom frame, thus actuating the picker sticks alternately to throw the shuttle. The picker stick which receives the impact of the shuttle will be thereby rocked to force the piston connected therewith in an inward direction, thus forcibly expelling the air contained in the cylinder of such piston, the escaping air forming a cushion whereby the force of the impact of the shuttle is relieved, and the operation is steadied, and undue vibration is avoided.

Suitably arranged springs S may be used 20 to assist the return movement of the piston 4.

Having thus described the invention, what is claimed as new, is:—

In a loom, two cylinders supported in axial alinement below the lay of the loom, a supply pipe communicating with a source of supply of compressed air, said supply pipe being disposed below and in axial

alinement with the cylinders, a branch pipe 30 extending from and at right angles to said supply pipe, inlet pipes connecting said branch pipe with the heads at the inner ends of the two cylinders, each of said inlet pipes being provided with a valve casing disposed transversely thereof and in registry with the axial lines of the cylinders, valves operating in said casing and adapted to alternately connect the interior of the cylinders with the compressed air supply and with the outer atmosphere, means for reciprocating said valves in opposite directions to one another, spring-actuated pistons operating in the cylinders and having stems extending through the heads at the outer ends of said cylinders, brackets extending from the frame of the loom, and picker sticks supported pivotally upon said brackets, the lower ends of said picker sticks being operatively connected with the outer ends of the piston stems.

In testimony whereof I affix my signature in presence of two witnesses.

JOHN W. KIRKUS.
